UNITED STATES PATENT OFFICE.

HARRY A. DOUGLAS, OF BRONSON, MICHIGAN, ASSIGNEE TO DOUGLAS & RUDD MANUFACTURING COMPANY, OF BRONSON, MICHIGAN, A CORPORATION OF MICHIGAN.

TERMINAL CONNECTOR.

1,190,524.

Specification of Letters Patent.

Patented July 11, 1916.

Application filed August 5, 1913, Serial No. 783,158. Renewed May 19, 1916. Serial No. 98,679.

To all whom it may concern:

Be it known that I, HARRY A. DOUGLAS, citizen of the United States, residing at Bronson, in the county of Branch and State 5 of Michigan, have invented a certain new and useful Improvement in Terminal Connectors, of which the following is a full, clear, concise, and exact description, reference being had to the accompanying drawings, forming a part of this specification.

My invention relates to terminal connectors useful in coupling sections of flexible connectors for conveying current to translating devices, such as electric lamps, though 15 the invention is not to be limited to the interposition of flexible conductors between the terminal connectors and the translating devices.

The invention has for its general object 20 the provision of a terminal connector whose parts are of simple construction readily assembled and disassembled and by which firm electrical connection is effected between conducting wires and the parts that are to 25 be included in circuit therewith.

I will explain my invention more fully by reference to the accompanying drawing showing the preferred embodiment thereof and in which—

30 Figure 1 is a view of the plug and socket portions of the connector in separated relation and in longitudinal section; Fig. 2 is a view of these parts in the same relation, partially in section and partially in plan but taken in a direction at right angles to that in which Fig. 1 is taken; Fig. 3 is a sectional view on line 3 3 of Fig. 1; and Fig. 4 is a sectional view on line 4 4 of Fig. 1.

Like parts are indicated by similar characters of reference throughout the different figures.

In the drawing the invention is shown as being embodied in a wire terminal connector located between portions of a flexible conductor, though it is obvious that the terminal connector may be otherwise located, the invention not being limited to the interposition of the flexible conductor between the translating device and the terminal connector of my invention which is to furnish current to the translating device. The connector illustrated also includes plug and socket portions each having structural features embraced in my invention but the invention is not to be limited to a connector in

which both the plug and socket portions have the novel characteristics, the invention being embraceable within either such portion. The socket illustrated also includes structural characteristics which are set 60 forth in my co-pending application Serial No. 776,217, filed June 28, 1913.

The plug terminal connector shown includes a metal plug 1 provided with an axial recess 2 formed in accordance with the invention disclosed in my co-pending application Serial No. 783,159, filed August 5, 1913. The metal plug 1 desirably has a smooth cylindrical portion which projects endwise through the insulating sleeve 3, this cylindrical portion of the plug 1 having a circular outsetting flange 4, the cylindrical and flanged portions of the plug 1 having snug fit with the bore of the sleeve 3 which is correspondingly shaped. The end of the 75 sleeve 3 opposite to that through which the plug 1 projects is threaded upon its interior there to have threaded engagement with a metal sleeve 5 having an annular recess 6 near its outer end formed by turning 80 a groove in a manner to leave an outer flange 7 upon the sleeve 5. Another sleeve of insulation 8 is forced, at its inner end, into the groove 6, the sleeves 3 and 8 having butt engagement at their adjacent end 85 faces. When the parts 3 and 5 are tightly screwed together the plug 1 is projected sufficiently through the left end of the sleeve 3 to enable it to make proper contact with a suitable complementary terminal 9, the 90 smooth fit of the element 1 and 3 readily permitting this result. The rigid assembly of the parts 1, 3 and 5 thus effected is maintained by the consequent tight engagement between the sleeve portions 3 and 8.

The metal plug 1 includes an inner perforated stem 10 through the perforation 10¹ of which an end portion of a circuit conducting wire 11 is passed so that the extreme end portion of this wire will lie upon one 100 side of the stem and a continuing portion of this wire will lie upon the other side of the stem. The bore of the sleeve 5 is of a diameter sufficiently small to engage the wire 11 upon both sides of the stem 10 with sufficient frictional pressure to occasion very firm electrical contact of the wire 11 with the stem 10 and the sleeve 5 whereby the wire 11 is brought into and maintained in firm electrical connection with the plug 1 110

without the aid of solder or screw clamping means in threaded connection with the plug 1. The bore of the sleeve 8 is of a size sufficient to receive the insulating covering 12 provided for the wire 11, the bore of the sleeve 5 being desirably, though not necessarily, of similar diameter so that the covering 12 may also project therein.

The invention being shown in the form of 10 a coupler for joining portions of the flexible conductor, the contact 9 complementary to the contact 1 (and here shown as being constructed in accordance with my co-pending application Serial No. 776,217, filed June 15 28, 1913) is inclosed by a shell 13 and is mounted upon a sleeve 14 of this same material tightly received within the shell 13. Contact 9 is pressed forwardly by a coiled spring 15 bottomed in a metallic sleeve 16, 20 current being carried through the sleeve 16 and the spring 15 to the terminal contact 9. The metal shell 13 projects from the insulating sleeve 14 and is provided with bayonet slots 17 which are adapted to receive 25 bayonet pins 18 carried by the adjacent end of the insulating sleeve 3. When the pins 18 are home in the slots 17 the metal plug 1 presses the terminal 9 inwardly against the force of the spring 15 whereupon the circuit is completed, the connector shown being 30 a single pole connector, though it is obvious that the invention is not to be limited to this single pole device.

The metal sleeve or spring barrel 16 has 35 a smooth cylindrical portion which projects endwise into the insulating sleeve 14, this cylindrical portion of the sleeve 16 having a circular outsetting flange 17¹, the cylindrical and flanged portions of the sleeve 16 having 40 snug sliding fit with the bore of the sleeve 14 which is correspondingly shaped. The end of the sleeve 14 opposite to that through which the sleeve 16 projects is threaded upon its interior so as to have threaded engagement, a metal sleeve 18 having an annular recess 19 near its outer end formed by turning a groove in a manner to leave an outer flange 20 upon the sleeve 18. Another sleeve 45 of insulation 21 is forced, at its inner end, into the groove 19, the sleeves 14 and 21 having butt engagement at their adjacent end faces. When the parts 14 and 18 are tightly screwed together the sleeve 16 is forced into 50 tight engagement with the sleeve 14 properly to position the spring pressed contact 9, the smooth fit of the elements 14 and 16 readily permitting this result. The rigid assembly of the parts 16, 14 and 18 thus effected is maintained by the consequent tight engagement between the sleeve portions 14 and 21.

The metal sleeve 16 is provided with an inner perforated stem 22 through the perforation 22¹ of which an end portion of a circuit conducting wire 23 is passed so that

the extreme end portion of this wire will lie upon one side of the stem and a continuing portion of this wire will lie upon the other side of the stem. The bore of the sleeve 18 is of a diameter sufficiently small to engage 70 the wire 23 upon both sides of the stem 22 with sufficient frictional pressure to occasion very firm electrical contact of the wire 23 with the stem 22 and the sleeve 18 whereby the wire 23 is brought into and maintained in firm electrical connection with the sleeve 16 without the aid of solder or screw clamping means in threaded connection with the sleeve 16. The bore of the sleeve 21 is of a size sufficient to receive the insulating covering 24 provided for the wire 23, the bore of the sleeve 18 being desirably, though not necessarily, of similar diameter so that the covering 24 may also project therein. 75

In the case of both the plug and socket, 80 where the elements 5 and 18 are made of metal, an electrical connection between the wires and the conducting portions 1 and 16 is further insured by the engagement of the flanges 4 and 17¹ respectively with the sleeves 5 and 18. 85

It will be observed that the parts are of simple construction and readily assembled without impairing the desired thorough electrical connection. The parts are also very 90 readily separated for the purpose of repair and replacement.

Reference may be had to my co-pending applications as follows: Serial No. 713,317, filed August 5, 1912, Serial No. 714,207, 100 filed August 9, 1912, and Serial No. 776,217, filed June 28, 1913.

While I have herein shown and particularly described the preferred embodiment of my invention I do not wish to be limited to 105 the precise details of construction shown, as changes may readily be made without departing from the spirit of my invention, but—

Having thus described my invention I 110 claim as new and desire to secure by Letters Patent the following:—

1. A terminal connector including a flanged portion through which circuit is to be extended, which portion includes an apertured stem; a conducting wire having an end projected through the aperture of said stem so as to have parts thereof lie upon opposite sides of the stem; a sleeve having a bore in which said portion may slide and shaped to engage the flange of said flanged portion to limit the extent of relative movement of the sleeve and flanged portion; a second sleeve in threaded engagement with the first and in butt engagement with the flange to maintain 120 the flanged portion and the first sleeve in firm connection, the bore of the second sleeve receiving the wire and stem and being of such diameter as to enable the second sleeve to maintain the wire in firm electrical connection. 125

nection with the stem, the second sleeve being grooved at its outer end; and a third sleeve received in the groove of the second sleeve and having butt engagement with the 5 first sleeve.

2. A terminal connector including a flanged portion through which circuit is to be extended, which portion includes an apertured stem; a conducting wire having an 10 end projected through the aperture of said stem so as to have parts thereof lie upon opposite sides of the stem; a sleeve, which is of insulating material, having a bore in which said portion may slide and shaped to engage the flange of said flanged portion to limit the extent of relative movement of the 15 sleeve and flanged portion; and a second sleeve in threaded engagement with the first and in butt engagement with the flange to 20 maintain the flanged portion and the first sleeve in firm connection, the bore of the second sleeve receiving the wire and stem and being of such diameter as to enable the second sleeve to maintain the wire in firm 25 electrical connection with the stem.

3. A terminal connector including a flanged portion through which circuit is to be extended, which portion includes an apertured stem; a conducting wire having an 30 end projected through the aperture of said stem so as to have parts thereof lie upon opposite sides of the stem; a sleeve having a bore in which said portion may slide and shaped to engage the flange of said flanged 35 portion to limit the extent of relative movement of the sleeve and flange portion; and a second sleeve provided with means for forcing it in butt engagement with the flange to maintain the flanged portion and the first 40 sleeve in firm connection, the bore of the second sleeve receiving the wire and stem and being of such diameter as to enable the second sleeve to maintain the wire in firm 45 electrical connection with the stem.

4. A terminal connector including a flanged portion through which circuit is to be extended, which portion includes an apertured stem; a conducting wire having an end 50 projected through the aperture of said stem so as to have parts thereof lie upon opposite 55 sides of the stem; a sleeve having a bore in which said portion may slide and shaped to engage the flange of said flanged portion to limit the extent of relative movement of the sleeve and flanged portion; and a second 60 sleeve in threaded engagement with the first sleeve and in butt engagement with the flanged portion to maintain the flanged portion and the first sleeve in firm engagement.

5. A terminal connector including a flanged portion through which circuit is to be extended, which portion includes an apertured stem; a conducting wire having an end 65 projected through the aperture of said stem so as to have parts thereof lie upon opposite 70 sides of the stem; a sleeve having a bore in which said portion may slide and shaped to engage the flange of said flanged portion to limit the extent of relative movement of the sleeve and flanged portion; and a second 75 sleeve in threaded engagement with the first sleeve and in butt engagement with the flanged portion to maintain the flanged portion and the first sleeve in firm engagement.

6. A terminal connector including a flanged portion through which circuit is to be extended, which portion includes an apertured stem; a conducting wire having an end 80 projected through the aperture of said stem so as to have parts thereof lie upon opposite 85 sides of the stem; a sleeve having a bore in which said portion may slide and shaped to engage the flange of said flanged portion to limit the extent of relative movement of the sleeve and flanged portion; and a second 90 sleeve in threaded engagement with the first sleeve and in butt engagement with the flanged portion to maintain the flanged portion and the first sleeve in firm engagement, the bore of one of said sleeves receiving the wire and stem and being of such diameter as to engage the wire and maintain it in firm 95 electrical connection with the stem.

6. A terminal connector including a flanged portion through which circuit is to be extended, which portion includes an apertured stem; a conducting wire having an end projected through the aperture of said stem so as to have parts thereof lie upon opposite sides of the stem, there being means for holding the wire in position; a sleeve having a bore in which said portion may slide and shaped to engage the flange of said flanged portion to limit the extent of relative movement of the sleeve and flanged portion; and means for clamping said flange and sleeve together.

In witness whereof, I hereunto subscribe my name this 30th day of July A. D. 1913.

HARRY A. DOUGLAS.
